UNITED STATES PATENT OFFICE.

ELTON WITHROW AND DAVID LLOYD DAVIS, OF PORTLAND, OREGON.

GARMENT-SUPPORT.

1,261,334.

Specification of Letters Patent.

Patented Apr. 2, 1918.

Application filed March 24, 1916. Serial No. 86,389.

To all whom it may concern:

Be it known that we, ELTON WITHROW and DAVID LLOYD DAVIS, citizens of the United States of America, and residents of 5 Portland, in the county of Multnomah and State of Oregon, have invented certain new and useful Improvements in Garment-Supports, of which the following is a specification.

10 This invention relates to garment hangers and particularly to a device for supporting coats and the like.

An object of this invention is to provide 15 a foldable garment support having the general configuration or slope of the shoulders of a person, the body of the device being formed of fibrous material such as paper or cardboard having interlocking members for holding material in folded position to form

20 a garment support.

A further object of this invention is to provide means whereby a hook is applied to the form so that it may be suspended when the garment is being hung.

25 A still further object of this invention is to provide means whereby trousers or skirts may be suspended from the support when the same are provided with buttons or other hanger engaging members adapted to coact 30 with the means provided for the engagement of such buttons or devices.

With the foregoing and other objects in view, the invention consists in the details of construction, and in the arrangement and 35 combination of parts to be hereinafter more fully set forth and claimed.

In describing the invention in detail, reference will be had to the accompanying drawings forming part of this specification 40 wherein like characters denote corresponding parts in the several views, and in which—

Figure 1 illustrates a perspective view of the garment support;

Fig. 2 illustrates a perspective view of the opposite side from that shown in Fig. 1;

Fig. 3 illustrates a vertical sectional view;

Fig. 4 illustrates a plan view of the blank prior to being folded;

Fig. 5 illustrates a fragment of the hanger 50 in a partially folded state; and

Fig. 6 illustrates a perspective view of a fragment of the hanger partially folded.

In producing the hanger or form, I utilize a blank 7 of fibrous material, preferably 55 relatively stiff paper or card-board of the

general configuration shown in Fig. 4 in which there are two wings 8 and 9, the former of which has a tongue 10 and the latter of which has a slot 11 to receive the tongue when the blank is folded.

The dotted lines 12, 13, 14, 15, 16, 17, 18, 19, 20, 21, 22, 23, 24, 25 and 26 illustrate folds on which the blank is bent to produce the form and the blank is preferably creased on these lines to facilitate the folding operation. At the intersection of the dotted lines 17, 18, 20, 21, 23, 24, 25 and 26, there is an aperture A which, when the blank is folded forms a clearance for the shank of a hook to be presently described.

The wings 8 and 9, are further provided with tongues 27 and 28 respectively which enter slots 29 and 30 respectively when the flank is folded.

The blank has two arc-shaped slots or 75 slits 31 and 32 producing tongues 33 which may be bent or pressed out of alinement with the body of the blank so that buttons on trousers or skirts may be pressed to lie on the inside of the blank for suspending 80 garments of this character.

The blank is folded on the score lines to produce the shape shown in Figs. 1 and 2 and the manner of folding the several portions of the blank is illustrated in Figs. 3, 5 85 and 6, it being understood that when the blank is folded it is held in its folded condition by reason of the fact that the tongue 10 is placed in the slot 11 and the tongues 27 and 28 enter the slots 29 and 30 respectively. 90

Previous to the securing of the blank in its folded position, a hook 35 is applied to the form, the said hook having, as here shown, a triangular inner end 36 which engages the wall of the pocket 37 formed by 95 the bends on the lines 23, 24, 25 and 26.

It has been found in practice that coat hangers produced in the manner stated are very light and comparatively inexpensive, yet afford such strength and durability as to 100 prove effective and satisfactory in use.

We claim:

1. In a garment support, a blank of fibrous material having wings, one of said wings having a slot therein, a tongue on the 105 other wing adapted to enter said slot, tongues on the wings, said blank having slots therein for the reception of the tongues of the wings when the blank is folded, said blank having arc-shaped slots producing 11

openings for the reception of buttons whereby a garment is supported, and a hook secured in the body of the hanger.

2. In a garment support, a blank of fibrous material having wings, one of said wings having a slot therein, a tongue on the other wing adapted to enter said slot, tongues on the wings, said blank having slots for the reception of the said tongues of the wings when the blank is folded, said blank having arc-shaped slots producing openings for the reception of buttons whereby a garment is supported, said blank being fold-

able to form a pocket, a hook having a triangular end lying in the pocket and adapted to engage the walls of said pocket, said hook extending through the upper edge of the hanger. ¹⁵

In testimony whereof, we affix our signatures in the presence of two witnesses.

ELTON WITHROW.
D. LLOYD DAVIS.
